UNITED STATES PATENT OFFICE.

CORINNA THACHER ROGERS, OF ANSONIA, CONNECTICUT, ASSIGNOR OF
ONE-HALF TO WILLIAM H. PLUMB, OF SAME PLACE.

DESIGN FOR A SACHET-BAG.

SPECIFICATION forming part of Design No. 19,774, dated April 22, 1890.

Application filed March 27, 1890. Serial No. 345,595. Term of patent 7 years.

To all whom it may concern:

Be it known that I, CORINNA THACHER ROGERS, a citizen of the United States, residing at Ansonia, in the county of New Haven and State of Connecticut, have invented a certain new and original Design for Sachet-Bags, of which the following is a specification, reference being had to the accompanying drawing, forming a part thereof, and which

5 shows a sachet-bag conformed and ornamented in accordance with my design.

The leading features of my design consist in the representation of a scallop shell, a puffed and gathered margin which extends around about the edge of the said shell, and a bow at

10 the top of said shell.

At the center of the sachet is the representation of a scallop shell *a*, and *b* is an out-

wardly-projecting puffed and gathered edge of textile material, which is represented as 20 held down by the edge of the scallop shell. At the top of the sachet, and represented as joining the puffed margin or bag in the shell, is a bow *c*, whose ends project oppositely from the central knot, one of said ends bearing the 25 representation of flowers *d*.

I claim—

The design for sachet-bags and similar articles, substantially as herein shown and described.

In testimony whereof I affix my signature in presence of two witnesses.

CORINNA THACHER ROGERS.
